United States Patent

Des. 238,128
Patented Dec. 23, 1975

238,128

KIOSK

Richard D. Marquette, Prairie Village, Kans., assignor to Trio, Incorporated, Overland Park, Kans.

Filed Oct. 12, 1973, Ser. No. 406,086

Term of patent 14 years

Int. Cl. D6—04

U.S. Cl. D6—169

FIG. 1 is a perspective view of two of the three identical sides of a kiosk showing my new design;

FIG. 2 is a side elevational view of the side which is not identical to the sides shown in FIG. 1; and

FIG. 3 is a top plan view.

I claim:

The ornamental design for a kiosk, as shown and described.
